CONTROL MECHANISM FOR HONING MACHINES

Harry J. Caldwell, Rockford, Ill., assignor to Barnes Drill Co., Rockford, Ill., a corporation of Illinois

Application April 15, 1943, Serial No. 483,111

14 Claims. (Cl. 51—34)

The invention relates to honing machines and more particularly to improved control mechanism for such machines.

One object of the invention is to provide improved control mechanism for automatically controlling the operations of a honing machine such as the relative reciprocation of the tool and work, the expansion and contraction of the tool and the disassociation of the tool and work at the termination of the honing cycle, which mechanism is simpler construction, less expensive to manufacture and easier to maintain in proper operating condition than the control mechanisms heretofore available.

Another object is to provide control mechanism of the above general character which can be adjusted very quickly and easily for any class of work within the capacity of the machine.

Still another object is to provide reciprocation controlling mechanism particularly suitable for honing machines adapted to be driven selectively to traverse the tool through either long or short working strokes of uniform length.

A further object is to provide control mechanism operable to concentrate the action of the honing tool at any selected area of the work to remove high spots, taper or other localized irregularities.

Other objects and advantages of the invention will become apparent from the following detailed description of the preferred embodiment illustrated in the accompanying drawings in which:

Figure 1 is a perspective view of a honing machine equipped with control mechanism embodying the features of the invention.

Fig. 2 is a sectional view taken in a vertical plane substantially on the line 2—2 of Fig. 1 showing details of the improved control mechanism.

Fig. 3 is a sectional view taken in a horizontal plane substantially on the line 3—3 of Fig. 2.

Fig. 4 is a front view of the control mechanism.

Fig. 5 is a sectional view taken in a horizontal plane substantially on the line 5—5 of Fig. 4.

Fig. 6 is a view partly in section taken in a vertical plane substantially on the line 6—6 of Fig. 3.

Fig. 7 is a diagrammatic view showing the positions of the control elements at the termination of an operating cycle.

Fig. 8 is a diagrammatic view showing the positions of the control elements at the beginning of an operating cycle but before the tool and work are operatively associated.

Fig. 9 is a diagrammatic view showing the posi-

tions of the control elements at the upper end of a working stroke.

Fig. 10 is a diagrammatic view showing the electrical and hydraulic operating and control circuits of the machine.

For purposes of illustration, the invention has been shown in the form most suitable for application to a pressure fluid actuated, vertical type honing machine. It will be understood, of course, that the invention is not limited to use in this specific type of honing machine but may be readily applied to other types of honing machines as well as to other comparable machine tools. It will also be understood that various modifications and adaptations may be made in the form, construction and arrangement of the parts of the improved control mechanism without departing from the spirit and scope of the invention as expressed by the appended claims.

Referring to Figs. 1 and 10 of the drawings, the machine selected to illustrate the application of the invention comprises a hollow, vertical column 11 mounted on a base 12 and having on its front face a pair of parallel guide members 13 forming a guideway for a vertically reciprocable tool support or head 14. The head, in this instance, is equipped with a single rotatable spindle 15 which carries a conventional internal honing tool 16 at the end of an elongated tubular driver 17. A motor M (Fig. 10) mounted in the column 11 is arranged to drive the spindle through the medium of a splined shaft 18 and suitable gearing 19, a part of which is enclosed in the upper end of the column and the remainder of which is enclosed in the head 14.

An adjustable work table 20, mounted on the machine base below the head 14, is adapted to support a workpiece W, such as a cylinder, in position to be operated on by the honing tool 16. In the particular machine illustrated, the honing operation is performed by rotating and simultaneously reciprocating the tool while the work is held stationary. Reciprocation of the tool is effected, in this instance, by pressure fluid actuated means including a cylinder 21 (Fig. 10) mounted within the column 11 and having a working piston 22 connected by a rod 23 with a rigid arm 24 projecting from the rear of the head.

Pressure fluid is supplied to the cylinder 21 by a pump P driven by a motor M—herein shown as connected in a parallel circuit with the spindle driving motor M. The pump is arranged to draw fluid from a reservoir R and to deliver it under pressure by way of a duct 25 to a two-position reversing valve V which directs the fluid selectively

to either the upper or lower end of the cylinder while connecting the other end of the cylinder to a drain line 26. The reversing valve may be of any suitable type and as herein shown is adapted to be shifted between its alternate positions by pressure fluid supplied under control of a pilot valve PV.

The pump P also supplies pressure fluid by way of a branch duct 28 to a cylinder and piston actuator 27 mounted in the head 14 and adapted in well-known manner to expand and contract the honing tool 16. The delivery of fluid to the actuator 27 is controlled by a conventional two position valve V-1. The valve, as shown, is spring biased to a tool contracting position and is adapted to be shifted to a tool expanding position by solenoid SOL-1.

The invention provides control mechanism of simple, rugged construction for actuating the pilot valve PV, the control valve V-1 and other control instrumentalities so as to run the machine through a complete operating cycle. The operating cycle is initiated manually and, in practice, ordinarily begins with the head in a retracted position and the tool contracted and withdrawn a substantial distance from the work. Upon manipulation of a cycle starting control device, in this instance a push button actuated switch S (Fig. 10), a relay R is energized to close a switch R-11 and thereby complete a current supply circuit for the motors M and M-1. The relay also closes a switch R-12 to complete a holding circuit for itself. This circuit includes an automatically operable stop switch S-1, an "inching" switch S-2 and a manually operable stop switch S-3. The relay R is maintained energized and the motors continue to run after the starting switch is released.

Coincident with the starting of the pump motor, the head 14 is shifted downwardly to carry the tool 16 into the work. As the tool enters the work the control mechanism acts to shift the valve V-1 to expand the tool and thereafter actuates the pilot valve PV periodically to cause the tool to be traversed repeatedly in a working stroke from one end of the work to the other. After a predetermined interval or a predetermined number of working strokes, the tool is contracted by appropriate actuation of the valve V-1 and then is withdrawn from the work by shifting the head back to its starting position. When the head reaches the fully retracted position the motor circuits are opened to stop the machine.

The control mechanism of the present invention automatically executes the various controlling actions required to produce the operating cycle above described. In its preferred form, the mechanism comprises a control member herein shown as a circular disk 30 adapted to be oscillated or rocked first in one direction and then in the other direction in timed relation to the reciprocation of the head 14 and through an arc accurately proportioned to the range of movement of the head. To this end, the disc is fixed on the outer end of the rockshaft 31 operatively connected with the head. The shaft is journaled in a bearing 32, carried on a bracket 33, located in a recess opening in one side of the machine column. As shown in Fig. 2, the bracket is attached to a frame member 34 which may be bolted or otherwise removable secured to the column so that the entire control assembly may be installed in or removed from the recess as a unit for convenience of assembly and maintenance. A cover plate 34' having a circular opening or window aligned with

the control disk is attached to the outer surface of the frame to cover the control mechanism.

Any suitable means may be utilized for operatively connecting the shaft 31 with the head. In the exemplary form of the mechanism, the connecting means comprises an endless chain 35, running over a sprocket wheel 36, splined to the shaft 31, and a second sprocket wheel 37 (Fig. 10) rotatably supported in the upper end of the machine column. The sprocket wheels are positioned so that one run of the chain is substantially parallel to the reciprocatory path of the head and one of the chain links in the parallel run is securely anchored to a rigid arm 38 projecting rearwardly from the head. The reciprocatory movements of the head are thus transmitted through the chain and the sprocket wheel 36 to the rock-shaft 31 and to the control disk 30 mounted thereon.

20 Loosely mounted on the shaft 31 within a counter bore in the bracket 33 is a control member 40 (Figs. 2 and 5) in the form of a sleeve having a flange 41 at its outer end. Fixed to the inner side of the flange is a cam lug 42 (Figs. 3 and 6) adapted to coat with a follower 43 carried on one arm of the bell crank lever 44 supported by a pivot pin 45 on an extension 46 of the bracket 33. The other end of the lever is connected by a link 47 and a rod 48 with the actuating member of the 25 pilot valve PV. A spring 49 secured at one end to the lever and at the other end to a stationary part of the supporting structure urges the follower against the cam. The arrangement is such that the spring tends to shift the pilot valve into a position to effect a downward movement of the head. As the cam sleeve is turned to the position shown in Fig. 6, the cam lug 42 rocks the lever 44 in a counterclockwise direction to shift the pilot valve 30 into its alternate position and thereby reverse the 35 direction of movement of the head.

The valve shifting movements for defining the upper and lower limits of the working stroke of the tool are imparted to the sleeve member 40 by the control disk 30 through the medium of suitable dogs including a lower limit dog 50 and an upper limit dog 51. The dogs are adjustably secured in a circular T-slot 52 in the face of the disk and are arranged to project radially beyond the edge of the disk for alternate engagement with 45 a forwardly extending finger 53 formed on a radial arm 54 rigidly anchored to the flange 41 of the cam sleeve.

In the initial downward movement of the head at the beginning of an operating cycle, the cam lug 42 and arm 54 occupy the position shown in Fig. 8 while in subsequent downward working strokes these parts occupy the position shown in Fig. 9. As the head approaches the end of the downward stroke, the dog 50 engages the finger 60 53 to swing the arm and cam lug to the position shown in Fig. 10, thereby shifting the pilot valve to reverse the direction of movement of the head. As the tool approaches the upper end of the working stroke, the dog 51 engages the finger 53 and shifts the cam lug to the position shown in Fig. 9 to interrupt the upward movement of the head and initiate a downward movement instead. In this way, the dogs alternately act to rock the cam sleeve and confine the movements of the head within a predetermined working range. A spring 65 pressed friction detent 55 (Fig. 2) prevents overthrow of the cam sleeve and also acts to hold the sleeve in the positions to which it is moved by the dogs.

70 By reason of their adjustable mounting, the

dogs 50 and 51 can be readily shifted around the disk so as to engage the finger 53 at any selected points in the range of travel of the toolhead. Accordingly, both the upper and lower limits of the working stroke and, of course, the length of the stroke can be adjusted to any selected value within the range of the machine. To facilitate such adjustment the dogs are formed with tail pieces 56 positioned to register with a scale 57 on the face of the disk calibrated to represent the full 10 range of travel of the toolhead.

When the head is shifted to retracted position for withdrawing the tool from the work, the dog 51 carries the finger 53 and arm 54 through a correspondingly longer arc to the position shown in Fig. 7. The movement of the arm through this extended range is utilized for controlling the expansion and contraction of the honing tool. For this purpose a cam plate 58 is secured to the lower end of the arm with its arcuate lower edge positioned to coact with the actuator 59 of a switch S-4 controlling the circuit of the solenoid SOL-1. The edge portion of the cam plate is dimensioned so as to engage the actuator and hold the switch closed while the cam sleeve is rocked between the limits shown in Figs. 9 and 10 corresponding to the upper and lower limits of the working stroke of the tool. Accordingly, the solenoid is energized and the tool is expanded as it enters the work and expansion is maintained until withdrawal of the tool from the work is initiated.

Means is provided for temporarily relieving the cam sleeve of control over the pilot valve to effect the withdrawal of the tool from the work and the consequent extended movement of the control disk 30. This means, as herein shown, comprises a solenoid SOL-2 (Figs. 6-10) mounted on an upright extension 61 of the bracket 33. The solenoid has an armature 62 connected by a link 63 with one arm of a bell crank lever 64 fulcrumed as at 65 on the frame extension. A pin 66, carried on the other end of the arm, engages in a slot 67 in the link 47 to provide a lost motion connection with the pilot valve operating linkage. Upon energization of the solenoid, the bell crank is rocked in a clockwise direction to the position shown diagrammatically in Fig. 7, thereby shifting the pilot valve into a position to effect upward movement of the head. As long as the solenoid remains energized the spring 49 is rendered ineffective to shift the pilot valve to its "down" position. Accordingly, withdrawal of the cam lug 42 from the path of the follower 43 does not result in a downward movement of the head as normally occurs during the working portion of the cycle. Instead, the head continues its upward movement beyond the upper limit of the working stroke to the retracted position, thereby withdrawing the tool from the work. The energization of the solenoid SOL-2 may be controlled automatically as by a timer actuated switch TS or manually as by a push button switch S-5.

Provision is made for automatically stopping the machine when the head 14 reaches its fully retracted position. For this purpose a dog 68 is mounted on the control disk 30 in a position to engage the actuator 69 of the automatic stop switch S-1 previously referred to. Engagement of the actuator by the dog opens the switch to interrupt the circuit of the relay R which becomes deenergized and immediately opens the motor switch R-11, thereby stopping both motors. When the solenoid SOL-2 is released, the pilot valve is returned to the control of the spring

49 which shifts the valve to its "down" position thereby conditioning the machine for the next operating cycle.

In finishing a workpiece by the honing process, it is sometimes necessary or desirable to concentrate the abrasive action of the tool in a particular localized area to remove high spots, taper or other irregularities and thus true up the surface of the work. This operation, commonly known as "short-stroking," is carried out by rapidly reversing the head reciprocating mechanism. With the control mechanism heretofore available, a high degree of skill as well as extreme care on the part of the operator is required to obtain the uniform short reciprocating strokes required for accurately finishing the work. The control mechanism provided by the present invention embodies novel means whereby uniform stroking is effected automatically so that even a relatively unskilled operator may "short-stroke" satisfactorily. Moreover, the "short-stroking" may be localized at any desired point in the work within the range of travel of the tool.

To obtain the uniformity of stroke above referred to, means is provided in the control mechanism for coupling the rockshaft 31 directly to the pilot valve controlling cam sleeve 40 so that the latter is enabled to respond quickly and positively to relatively short movements of the head. The preferred means for effecting this coupling comprises a shiftable clutch element in the form of a ring 70 (Figs. 2 and 5) slidably supported on a hub 71 projecting from the rear face of the control disk 30. The inner face of the ring is formed with clutch teeth 72 adapted to be moved into engagement with clutch teeth 73 formed on the adjacent end of the cam sleeve.

The clutch ring is held against rotation relative to the shaft by a pair of guide pins 75 anchored in the ring and extending axially through bushings 76 seated in diametrical opposed recesses in the control disk. Springs 77 interposed between the bushings and nuts 78 threaded on the outer ends of the pins urge the latter to the left (as viewed in Fig. 2) and thus tend to yieldably hold the clutch ring in a disengaged position.

For shifting the clutch ring to engaged position, a pair of plungers 78 (Fig. 5) are slidably supported in bushings 79 fitted in recesses in the control disk on opposite sides of the hub 71. The inner ends of the plungers are arranged to abut against the outer face of the clutch ring while the inner ends are threaded in or otherwise rigidly secured to a cap member 80 carried on an endwise slidable rod 81 extending through an axial bore in the rockshaft 31. A compression spring 82 interposed between the disk and the cap member urges the latter outwardly to withdraw the plungers from engagement with the clutch ring and thus permit the springs 77 to shift the ring to disengaged position. The limit position to which the cap and plungers are shifted is shown in Fig. 2, this position being defined by a stop 83 (Fig. 5) fast on the end of the rod and arranged to coact with a fixed abutment 84 on the machine frame.

While any suitable means may be utilized for shifting the rod 81 to force the plungers against the clutch ring and thereby move the latter to engaged position, the invention provides manually operable means for this purpose. As herein shown, the shifting means comprises a hand lever 85 (Fig. 1) fixed on the end of a rockshaft 86,

disposed substantially at right angles to the rod 81 and projecting at the front of the machine. An eccentric pin 87 (Fig. 5) on the inner end of the shaft engages in a peripheral groove in a collar 88 fixed on the rod. Rocking movements of the shaft 86 are thus effective to shift the rod endwise and thereby move the associated clutch actuating elements to clutch engaging position.

With the above arrangement the clutch teeth may be engaged to couple the rockshaft and the cam sleeve in any selected position of the head. In other words, the coupling may be effected to initiate "short-stroking" at any point in the range of travel of the tool and, consequently, in any selected area of the workpiece upon which the tool is operating. Since the cam sleeve responds directly to the movements of the head when coupled with the shaft, and the pilot valve is reversed at very short intervals, the reciprocation of the head is confined within relatively narrow limits. As the valve operation is determined by the movements of the head, the length of the strokes imparted thereto will remain uniform at all times.

It will be apparent from the foregoing that the invention provides control mechanism of novel and advantageous construction particularly suitable for use with honing machines and comparable machine tools. The mechanism is extremely simple in construction and consequently inexpensive to manufacture and easy to maintain in proper operating condition. Adjustment of the mechanism for different classes of work is effected with the utmost convenience by merely shifting a set of control dogs with reference to a graduated scale on a conveniently accessible control disk. The invention also provides a novel control mechanism whereby selected areas of the work may be "short-stroked" to remove high spots, taper or other irregularities. In this operation the tool strokes are maintained uniform without any effort on the part of the operator, thus insuring accurate finish of the work.

I claim as my invention:

1. The combination in a honing machine having tool and work supports one of which is reciprocable by power actuated means, of control mechanism for the power actuated means including, a shaft rocked in timed relation to the movements of the reciprocable support, a control member having a hub portion rotatably mounted on said shaft for movement between two alternate positions, said member being operative in one position to initiate movement of the reciprocable support in one direction and in the other position to initiate movement of the support in the opposite direction, a disk fixed on said shaft adjacent said control member, a pair of radially projecting dogs mounted on said disk, and a radially extending arm rigid with said control member having a finger projecting forwardly at one side of said disk for engagement by said dogs alternately whereby the member is shifted between its two positions, said dogs being adjustable with respect to each other to vary the range of reciprocation of the support.

2. The combination in a honing machine having a tool support and a work support with power actuated means for reciprocating one of the supports, of control mechanism for controlling the power actuated means comprising, a cam member supported to rock about a horizontal axis, said member being operative in one position to initiate movement of the reciprocable support in one direction and in another position to ini-

tiate movement of the support in the opposite direction, a control member mounted forwardly of said cam member and oscillated about an axis coincident with the axis of said cam member in timed relation to the reciprocation of the support, a pair of radially projecting dogs adjustably mounted on the front face of said control member, and an arm rigid with said cam member having a finger projecting forwardly between said dogs for alternate engagement thereby in the oscillation of the control member whereby to rock said cam member between said two positions.

3. In a honing machine, in combination a support for a honing tool, a pressure fluid operated actuator operative to expand and contract the tool, a valve controlling the delivery of pressure fluid to said actuator, a support for work to be operated on by the tool, a second pressure fluid operated actuator operative to shift one of said supports toward and from the other support, a second valve for controlling the delivery of pressure fluid to the second actuator, control mechanism including a shaft adapted to be rocked first in one direction and then in the other direction in timed relation with the movements of said one support, a control member loosely mounted on said shaft and having cam elements effective to shift said valves, and dogs mounted on said shaft operative to impart the movements of the shaft to said control member, said dogs being individually adjustable to determine the range of movement of said one support and the point in such range at which the tool is expanded or contracted.

4. In a honing machine, in combination, a support for a honing tool, power actuated means on said support for expanding and contracting the tool, a support for work to be operated on by the tool, a second power actuated means adapted to shift one of said supports toward and from the other support, a shaft adapted to be rocked first in one direction and then in the other direction in timed relation with the movements of said one support, a sleeve member loosely mounted on said shaft having one cam element operative to control said first power actuated means and another cam element operative to control said second power actuated means, means for imparting the movement of said shaft to said sleeve member including a control disk fixed on said shaft, and a pair of dogs mounted on said disk for individual adjustment relative to each other and to said cam elements to determine the range of movement of said one support and to time the expansion and contraction of the tool with respect thereto.

5. In a honing machine, in combination, a support for a honing tool, power actuated means on said support for expanding and contracting the tool, a support for work to be operated on by the tool, a second power actuated means adapted to shift one of said supports toward and from the other support, a control member adapted to be rocked first in one direction and then in the other direction in timed relation with the movements of said one support, cam means for controlling the extent and direction of movement of said one support by said second power actuated means, said cam means additionally acting to control the expansion and contraction of the tool by said first power actuated means, and means carried by said control member for actuating said cam means, said actuating means being adjustable to vary the range of movement of said

one support and to time the expansion and contraction of the tool with respect thereto.

6. In a honing machine, in combination, a support for a honing tool, a support for work to be operated on by the tool, power actuated means operative to move one of said supports toward and from the other support, control means for said power actuated means including a cam member adapted to be rocked between two positions to control the direction of movement of said one support, a control member adapted to be rocked about a common axis with said cam member in timed relation with the movements of said one support, a pair of radially projecting dogs mounted on said control member, an arm rigid with said cam member alternately engageable by said dogs whereby said cam member is shifted between its two positions, and detent means frictionally engaging said cam member to hold it in either shifted position.

7. In a honing machine having tool and work supports one of which is reciprocable by power actuated means, control mechanism for said power actuated means comprising, in combination, a rotatably supported shaft, means operative to rock said shaft first in one direction and then in the other direction in timed relation to the movements of said one support and through an angle proportioned to the extent of movement of the support, a control disk fixed on said shaft, a control member supported for rotation about the axis of said shaft, means actuated by said member upon rotation through a relatively small angle to control the direction of movement of said one support, a radially projecting element rigid with said member, a pair of radially projecting dogs mounted on said disk in position to engage said element alternately and thereby impart rotative controlling movements to said member, said dogs being spaced apart to define the limits of the working stroke of said one support, and means operative to establish a direct driving connection between said shaft and said control member whereby the movements of said head are confined within a range substantially shorter than said working stroke.

8. In a honing machine having tool and work supports one of which is reciprocable by power actuated means, control mechanism for said power actuated means comprising, in combination, a rotatably supported control member adapted to be rocked through a relatively small angle to control the direction of movement of said one support, a second rotatably supported control member adapted to be rocked through an angle proportioned to the range of movement of said one support and in timed relation therewith, control elements mounted on said second member in spaced relation engageable alternately with said first member to rock the latter in opposite directions and thereby confine the movements of said one support within a predetermined working range, and other means for establishing a direct driving connection between said members whereby to confine the movements of said one support within a substantially shorter range.

9. In a honing machine having tool and work supports one of which is reciprocable by power actuated means, control mechanism for said power actuated means comprising, in combination, a rotatably supported control member adapted to be rocked through a relatively small angle to control the direction of movement of said one support, a second rotatably supported

control member adapted to be rocked through an angle proportioned to the range of movement of said one support and in timed relation therewith, control elements mounted on said second member in spaced relation engageable alternately with said first member to rock the latter in opposite directions and thereby confine the movements of said one support within a predetermined working range, clutch means engageable to drivingly couple said members whereby the second member is adapted to respond directly to the movements of said one support and thereby confine such movements within a narrow range, and means operable manually to engage said clutch means at any selected point in the working range of said one support.

10. Mechanism for controlling the reciprocation of a machine element comprising, in combination, a shaft adapted to be rocked first in one direction and then in the other direction in timed relation with the movements of the machine element, a first control member fast on said shaft, a second control member journaled on said shaft, a pair of dogs mounted on said first member in spaced relation, means on said second member adapted to be engaged alternately by said dogs to shift the member between two control positions, a clutch element supported on said first control member for movement axially of the shaft, a cooperating clutch element on said second control member, spring means yieldably urging the movable clutch element away from the other clutch element, and means operable manually to shift the movable clutch element into engagement with the other clutch element and thereby establish a direct driving connection between the shaft and said second control member.

11. Mechanism for controlling the reciprocation of a machine element comprising, in combination, a shaft adapted to be rocked first in one direction and then in the other direction in timed relation with the movements of the machine element, a first control member fast on said shaft, a second control member rotatably supported on said shaft, a pair of dogs mounted on said first member in spaced relation, means on said second member adapted to be engaged alternately by said dogs to shift the member between two control positions, a clutch element carried by each of said control members, and means for engaging said clutch elements to establish a direct driving connection between the shaft and said second control member.

12. Mechanism for controlling the reciprocation of a machine element comprising, in combination, a shaft adapted to be rocked first in one direction and then in the other direction in timed relation with the movements of the machine element, a first control member fast on said shaft, a second control member loosely mounted on said shaft, a pair of dogs mounted on said first member in spaced relation, means on said second member adapted to be engaged alternately by said dogs to shift the member between two control positions, and other means operative to establish a direct driving connection between said shaft and said second control member.

13. Mechanism for controlling the reciprocation of a machine element comprising, in combination, a control member adapted to be rocked first in one direction and then in the other direction through an angle proportioned to the normal range of movement of the machine ele-

ment and in timed relation to such movement, a second control member adapted to be rocked through a relatively small angle to control the direction of movement of the machine element, spaced elements carried by said first control member operable alternately to rock said second control member as the machine element approaches the limits of its normal range of reciprocation, and other means operative to establish a direct driving connection between said control members whereby the machine element is reciprocated within a range substantially shorter than its normal range.

14. Mechanism for controlling the reciprocation of a machine element comprising, in combination, a control member adapted to be shifted first in one direction and then in the other direction through a range proportioned to the nor-

mal range of movement of the machine element and in timed relation to such movement, a second control member adapted to be shifted in the same direction as said first member but through a substantially shorter range, means actuated by said second control member in its movements for controlling the direction of movement of the machine element, spaced dogs carried by said first member operative alternately to shift said second member as the machine element approaches the limits of its normal range of reciprocation, and means operative to couple said second member directly to said first member for movement therewith, said second member operating to confine the movements of the machine element within a range substantially shorter than its normal range of reciprocation.

HARRY J. CALDWELL.
